CARBONIZING DRIER

Frank B. Morrill, North Adams, Mass., assignor
to The James Hunter Machine Company,
North Adams, Mass., a corporation of Massa-
chusetts

Application October 17, 1932, Serial No. 638,136

12 Claims. (Cl. 34—48)

The invention relates to driers in general, and in particular to driers in which continuous sheet material such as textile fabric is caused to travel through an enclosure while subjected to heat and moving air currents, the material being caused to travel in a lengthy path within the enclosure in order to prolong its exposure to the conditions maintained therein.

In the type of driers of this order known as carbonizing driers, woolen fabrics while wet with an acid solution are exposed to currents of air at a relatively high temperature, to char all particles of vegetable matter remaining in the fabric and also to dry the fabric so as to permit the charred impurities to be readily removed from the cloth.

In these driers, the lengthy path for the fabric is provided through carrying the latter over a great number of cylindrical rolls longer than the width of the fabric, located alternately at top and bottom of the enclosure, so that the fabric passes through the drier in a zigzag path comprising a great number of parallel and oppositely traveling runs. It has been the practice to direct the blasts or currents of air, utilized to expedite the drying, in a direction transversely of the fabric and hence at right angles to the direction of travel of the fabric. This practice has several very great drawbacks, the most important of which is that it produces unequal drying through causing one edge or portion of the fabric to dry more rapidly than the other edge or portion, because subjected to different conditions of heat and air movement. Such uneven drying is a very serious disadvantage, because even a slight variation in the air flow across the face of the goods results in the unequal shading of previously dyed fabrics, and also a subsequent application of dye will not take evenly across the width of the fabric where the wet acid has been allowed to stay in the fabric different lengths of time. The essential requirement of uniformity of air action across the whole width of the fabric is inherently unattainable where the air is introduced from one or both sides and the cloth moves lengthwise, as this creates zones extending lengthwise in the fabric in which the action of the air is bound to differ. The solution, I have found, lies in blowing the air lengthwise of the fabric, as thus every point in the width of the fabric can be brought equally close to the discharge aperture for the air, leaving only the simple problem of obtaining uniform discharge of air from such aperture throughout the width of

Other disadvantages of the prior method of disposing the drying and carbonizing air draft transversely are that the air currents travelling across the fabric tend to drift or crowd the fabric sideways, folding or rolling up the cloth with resultant incomplete or unequal drying or carbonizing action, or even forcing the cloth or a portion of its width off from the ends of the rolls, with additional harmful results through tearing or marking the cloth, and otherwise interfering with the proper operation of the drier. In addition, the air-introducing or propelling devices and apparatus have of necessity been located at one side of the enclosure, thereby rendering difficult or preventing access to the drier from both sides, for the purpose of straightening out selvages or for repairing a broken seam, or for other purposes; while the presence of these devices at the side of the drier greatly increases the overall width of the drier and the floor space occupied. Further, the heated air when once passed over the fabric has been either discharged at once from the enclosure and wasted, in spite of its still useful heat and capacity for further moisture-absorption, or where used over again, it has been brought back to its point of reuse in a round-about path wholly removed from useful contact with the fabric and usually with wasteful loss of its heat.

The objects of the present invention are to avoid these and other drawbacks of existing carbonizing driers, and in addition to increase the working efficiency and rate of production of machines of this type.

To these ends, the invention comprises a carbonizing drier comprising a housing or enclosure, means for propelling continuous material therethrough, and means for producing currents of air within the housing which are directed lengthwise instead of transversely of the travelling material. Preferably these currents of air after travelling to their useful limit in one direction are brought back to the air-propelling means in a closed circulation path which returns along the fabric, so that the full measure of its heat and moisture-absorbing powers is realized. Desirably the housing interior is sub-divided so as to define a plurality of more or less distinct stages, each with its own air-circulation path, in which different conditions of temperature and moisture may be created and maintained; the sections thus representing the several stages may be wholly or partly independent of each other as concerns their supply of air, and may be subdivided either by the fabric or by means inde-

pendent thereof into pressure and suction chambers to define the path of air-circulation. Means may be provided for easily varying the ratio between the air discharged and the air recirculated in each stage. With the air currents directed wholly lengthwise of the fabric, the air-propelling and heating devices, contrived to deliver a uniform draft across the full width, can be located in line with the runs of the material, instead of having to be at one side of the material, and through being within the width of the working portion of the enclosure, the whole drier need be but little wider than the widest fabric to be operated upon, thereby reducing the overall width of the machine and saving floor space, and also permitting complete accessibility to the cloth within the drier from both sides of the machine at all times.

Screens may be located in the path of the air as it leaves the cloth and before it reaches the heating and propelling devices, to catch and retain any lint or dirt dislodged and picked up by the air currents. As another preferred feature of the invention, the air is delivered over the fabric from the air-propelling devices in improved manner so as to create a negative pressure at the adjacent surface of the fabric, thereby expediting the evolution and removal of moisture from the fabric. Other features of the invention are as will be made plain hereinafter.

30 An illustrative embodiment of the invention is shown in the accompanying drawings, in which:—

Fig. 1 is a side elevation of a carbonizing drier embodying the invention, with the panels forming the side of the housing removed.

Fig. 2 is a plan view.

Fig. 3 is an enlarged side elevation of the stage or section of the drier of Fig. 1 first entered by the fabric, also with the side panels removed to show the interior arrangements, especially its sub-division into pressure and suction chambers.

Fig. 4 is a detail showing the discharge or plenum chamber and the arrangement of nozzles adjacent the lower ends of the runs of fabric, employed to create a negative pressure and expedited drying action.

In the drawings, the housing is indicated generally at 1, being composed throughout of heat insulating material as is customary. The usual 50 slatted rolls 3 are located at two levels, respectively at the top and bottom of the housing interior, and the cloth 5, entering the housing at 7, passes alternately around a top and bottom roll until it emerges from the machine at 9. The 55 cloth within the housing is thus disposed in vertical and substantially parallel runs. Certain of the rolls 3 at the top of the machine are driven by means of chains 11 and appropriate sprockets, bevel gears 13, 15, shaft 17 and pulley 19, from 60 a suitable source of power, to propel the cloth through the drier, all as heretofore. The two sides of the housing are formed by panels 21 which are easily removable to give access to the interior of the housing from either side, and in 65 addition small doors 22 are provided in certain of the panels.

In accordance with the invention, the interior of the housing is divided into three stages by means of air-impervious baffles or partitions 23, 70 25, which extend clear across the housing interior from the removable panels at one side to those at the other, and below the lower level of rolls 3 down to the bottom of the housing or the floor on which the machine rests. The baffles 75 terminate at or about the level of the top row of

rolls, so that the cloth 5 may pass thereover in proceeding from one section to the next, and also so that there may be a certain amount of interchange or travel of the air between the several stages. Though there is a narrow aperture 5 always open at the proper level to permit the cloth to pass horizontally from the last top roll of the intermediate stage to the first top roll of the last stage, there is a continuation of the baffle above this passage for the cloth, in the shape of 10 a damper or swinging baffle as indicated at 27, which may be closed to prevent free travel of the air in either direction between the intermediate and the last stage, or may be opened to the desired degree to permit air interchange. The last 15 stage thus can be made independent of the others so far as air transfer or interchange is concerned; it is kept materially hotter and drier than the rest of the machine to serve as the baker which assures the proper completion of the carbonizing 20 action. This third stage or baker is provided with its own exhaust ports 29, through which the air may be exhausted by any suitable means, not shown, and at such rate as conditions may dictate, sufficient fresh air to make up for that withdrawn through exhaust port 28 being allowed to enter as indicated by the arrows through the slot at point 9 through which the cloth emerges from the housing; but at the same time, the adjustable baffle 27 may be opened to permit any 25 desired amount of air from the baker to pass in the opposite direction to the travel of the cloth over the top of baffle 23 and into the intermediate stage. Thus the baker may be either in series or in parallel with the other stages, or 30 may pass a part of its air serially into the intermediate stage while wasting the rest through port 29.

The other stages, which may be called the drier stages or sections to distinguish them, are arranged in series as regards the travel of the air; an exhaust port 31 is provided in the first stage close to the point at which the cloth enters the machine, and any suitable means (not shown) is employed to draw off the requisite quantity of 45 saturated air through this port to suit the conditions desired or met with within these stages. Make-up air is allowed to enter under atmospheric pressure through a preheater 33 in the top of the right hand side of the intermediate 50 stage, the air being warmed during its entry through passing over the pipes 35 and flanges of an extended-surface heater located athwart its path. As noted, the first and intermediate 55 stages are in communication through terminating the baffle 25 at the level of the top rolls, so that air from the intermediate section enters the first section to continue its useful work before being discharged through the exhaust 31.

Each stage or section is sub-divided by means 60 of a baffle or partition 37 extending from about the level of the top rolls 3 to a point below the level of the bottom rolls, and across the full width of the housing interior. At the bottom, each partition 37 reaches to the housing of a heater 65 39 through which air is forced by a number of blowers 41 connected by leaders 42 with the space beneath the heaters, and driven by a motor 43 or other suitable source of power, the blowers and heaters all being located within the working 70 width of the housing. The air currents issuing from each heater 39 are directed upwardly between and at each side of the bottom rolls 3 through nozzles 45 extending across the width of the machine and are caused to travel upward 75

under pressure from the blower in a direction generally lengthwise of the fabric as the latter is disposed in vertical runs above the heaters and nozzles. By using in each suction chamber a series of blowers 41 (as shown in connection with the first stage only) abreast across the width of the drier, the air-flow into the space below the nozzles 45 is made essentially uniform across the full width of the housing; the parts which compose the nozzles and which of course obstruct the passage of air between adjacent nozzles co-operate with the excess air-handling capacity given to the blowers to build up a pressure which equalizes itself throughout this space or chamber, and the resulting sheets of air discharged from the nozzles are uniform in intensity across the full width of the machine. The air passes around the selvages in equal and oppositely directed amounts and force to enter between the runs which are closed at the bottom by the lower rolls 3, proceeding thereafter in the same general upward direction, lengthwise of the fabric. It will be obvious that there are no unbalanced forces tending to drift or crowd the fabric sidewise, and the uniform distribution of the air currents over the entire surface of the fabric and around its selvages ensures even and equal drying. Proper space is left between the ends of the rolls and the adjacent interior sides of the housing to permit free travel of the air around the selvages.

The air rising above the top rolls 3 is drawn over the tops of the partitions 37 and sucked down through the adjacent chamber by the action of the blowers 41 located below this chamber, passing lengthwise down between the vertical runs of fabric in this chamber and performing its drying action in a manner exactly similar to that obtaining in the associated pressure chamber on the other side of baffle 37. It will thus be seen that the improved carbonizing drier resolves into an enclosure divided up into a plurality of sections or stages each of which is sub-divided into a pressure and a suction chamber with an interposed blower and heating device, the air being caused to travel lengthwise of and in contact with the fabric at all times, both in going from and returning to the air-propelling and heating devices. Each of the three sections or stages shown, with its intermediate baffle 37, defines an air-circulation path, as shown by the arrows, in practically the whole of which the air is in useful drying contact with the fabric; the rapid circulation keeps the temperature uniform and resists condensation of moisture throughout all parts of each section.

When operating under the best conditions, only a small proportion of the air circulating in each stage is in process of being withdrawn through the exhaust ports 29 and 31, as through withdrawing the minimum amount which will suffice to keep the air from becoming saturated and terminate its power to absorb moisture the heat economy of the machine is at its best. But under certain circumstances, to prevent the condensation of acid-laden moisture on the interior parts of the drier and the cumulative concentration of the acid in such condensed moisture, a largely increased rate of discharge of air from the drier is needed, in extreme cases even compelling the discharge of the air from one or more sections without any recirculation therein. To provide for this contingency met with in handling certain fabrics, the first and intermediate sections are provided with adjustable swinging baffles 28, which cooperate with the partitions 37 in these

two stages to close more or less completely as desired the passage over the cloth through which the air passes from one stage to the preceding stage counter to the travel of the cloth. The pintles of these baffles 28, as also is true of the baffle 27 aforesaid, extend outside the casing at 38, and are there equipped with adjusting arms 32 whereby the baffles may be opened or closed to the extent needed. As indicated by the arrows, the air normally entering the baker at 9 passes through the fan and heater and is exhausted in part through the exhaust port 29, and in part proceeds from the suction chamber of this stage under the baffle 27 and into the suction chamber of the intermediate stage, where 15 it is mixed with fresh air entering through the pre-heater 33 and with circulating air passing from the pressure chamber to the suction chamber of this stage beneath the baffle 28. A part of the air in the pressure chamber of this stage 20 passes over the baffle 25 and into the suction chamber of the first stage, and when discharged into the pressure chamber of this stage is in part wasted through the exhaust port 31 and in part returned for recirculation into the suction 25 chamber by passing under the baffle 28. As will readily be understood, by fully closing the baffles 28 all the air passing through the suction chamber and the fan of the intermediate stage can be forced upward through the pressure chamber 30 of this stage and caused to be discharged over the baffle 25 under the full and positive pressure of this fan into the suction chamber of the first stage, to be correspondingly wasted through the exhaust port 31, without any recirculation whatever in these two stages. A similar baffle 28 35 may be arranged over the partition 37 in the baker, if desired. Through the provision of these adjustable baffles 28, it will be seen that any desired ratio between the volume of air circulated in any stage and the air discharged from the stage can be attained to meet whatever conditions of drying or of condensation may arise. The heaters 39, preferably of the usual form comprising steam pipes with expanded surfaces 40 fixed in rectangular heads at opposite extremities are mounted in accordance with the invention at the bottom of the pressure chambers of the several stages in the horizontal relation shown, close to the nozzles 45 and spaced well above the floor. 45 With this arrangement, they are easily accessible from below at all times for cleaning and other purposes. Being supported on angles 40, as shown, they may even be slid out sidewise of the machine for greater facility in cleaning accumulated dust from their interstices, after detaching the steam leads at 44, 46.

In accordance with another phase of the invention, the efficiency and economy of the improved drier may be further increased through 60 the arrangement shown in Fig. 4 for delivering the air from the blowers 41 in thin sheets at high speed over the surface of the fabric as disposed in vertical runs in the pressure chamber of each section or stage. This arrangement constitutes an application of my invention set forth in my co-pending application for patent filed under date of August 16, 1932, Serial No. 629,009. The air forced through the heaters 39 is caused to issue at high speed in thin sheets extending 65 across the entire working width of the housing through nozzles 47, which direct these sheets as indicated by the large arrows in Fig. 4, over the surface of the fabric lengthwise of the latter in closely adjacent and parallel relation to the sur- 70 75

face, whereby the air at the adjacent surface of the fabric is aspirated and entrained by the high speed sheet of air and induced to move away from such surface, as indicated by the small arrows 5 in Fig. 4, noticeably reducing the air pressure at the proximate surface of the fabric below the general pressure prevailing within the pressure chamber, or in other words creating a negative pressure at such surface of the fabric, which 10 characteristically bows the cloth inwardly toward the blasts as they issue from the nozzles. Through this reduction in the air pressure adjacent the surface of the fabric, the evolution of moisture from the fabric and its removal from 15 the proximity of the surface is greatly expedited.

Screens 49 are located below the bottom rolls 3 in the suction chamber of each stage or section, so that all air entering the blowers 41 is freed 20 of lint, threads, and other dirt or flying matter picked up or dislodged by the moving air currents or the traveling fabric, and this lint, etc., is prevented from reaching the heaters 39 where 25 it would otherwise collect on the fins, extended surfaces, or steam pipes to create a dangerous fire hazard. The screens are horizontally disposed in guides 61 whence they may easily be slid out laterally for stripping upon the removal 30 of the appropriate side panels 21 of the housing; being horizontally disposed and capable of removal in the same position, they retain even during removal the matter collected on their upper surfaces.

What I claim as my invention is:—

1. A drier having in combination a housing, 35 means for propelling continuous material therethrough, baffle means sub-dividing the housing interior into a plurality of sections through which the material passes in sequence, a plurality of means for exhausting air from and supplying air to the sections, and means for putting one of such sections optionally into or out of communication with the rest in respect of its air without interrupting the air-supply to the rest.

2. In a carbonizing drier, in combination, a 40 housing sub-divided into a baker section and drier sections, means providing for air movement from one section to another, means for circulating the air in a closed path in each section, and means optionally putting the baker section 45 into series or parallel relation with the rest of the sections as regards air flow.

3. In a carbonizing drier, in combination, a housing sub-divided into a baker section and drier sections, independent inlets respectively supplying 45 fresh air to the baker and to the drier sections, means providing for air movement from one section to another, means for heating and circulating the air in a closed path in a plurality of sections and independent exhaust passages 50 venting air respectively from the baker and drier sections to the outside of the housing, means optionally putting the baker section into series or parallel relation with the rest of the sections as regards air flow, and means for pre-heating all air supplied to the drier sections when 55 in parallel relation before such air joins the air circulating within the housing.

4. A drier having in combination a housing, 60 means for propelling continuous material therethrough in oppositely-traveling successive runs, a plurality of air-propelling means arranged across the width of the housing and a pressure-equalizing chamber into which the plurality of air-propelling devices discharges, and having means distributing the propelled air uniformly across and

throughout the runs of material through obstructing the free egress of the air from such chamber.

5. A carbonizing drier having in combination a housing, means for propelling continuous fabric material therethrough in vertical runs, means dividing the housing interior into a plurality of laterally adjacent transverse sections in which independently controllable different conditions of heat and moisture can be maintained, means subdividing at least one section into pressure and suction chambers each containing a plurality of runs of fabric, and air heating means and a fan located in line with the vertical runs of the fabric, interposed between and below the two chambers and in conjunction therewith defining a closed recirculation path, said fan producing a current of air in each chamber lengthwise of the runs of fabric from beyond the ends of such runs, so that the heated air enters the pressure 10 chamber in an upward direction to blow against one surface of the fabric, and enters the suction chamber from beyond the ends of the runs to blow against the other surface of the fabric and then returns to the same fan through which it 15 had previously passed.

6. In a machine for drying and carbonizing relatively air-impervious woolen fabrics in traveling continuous sheet form, in combination, a housing, means dividing the housing interior into a plurality of sections extending transversely of the length of the machine, means dividing each section vertically and transversely into a pressure chamber and a suction chamber, a fan and air-heating means both interposed between and below and in line with the pressure and suction chambers of a section producing a recirculating blast of air traveling through the heating means and upward in the pressure chamber and in the opposite direction in the suction chamber back to 20 the same fan, and means disposing the fabric in vertical air-directing sheets in a plurality of spaced and parallel runs in the pressure and suction chambers so that the runs compel the air blast to travel lengthwise of the fabric in each 25 chamber from beyond the ends of the runs.

7. In a machine for drying and carbonizing relatively air-impervious woolen fabrics while traveling in continuous sheet form, in combination, a housing, means dividing the housing interior into a plurality of sections extending transversely of the length of the machine, means dividing each section vertically and transversely into a pressure chamber and a suction chamber, a plurality of air-propelling and heating means 30 arranged across the width of the housing and interposed between, below, and in line with the pressure and suction chambers of a section producing a recirculating blast of air traveling in one direction in the pressure chamber and in the 35 opposite direction in the suction chamber back to its respective air-propelling means, and means disposing the fabric in vertical air-directing sheets in a plurality of spaced and parallel runs in the pressure and suction chambers so that the runs compel the air blast to travel lengthwise of the fabric in each chamber from beyond the 40 ends of the runs.

8. In a machine for drying and carbonizing relatively air-impervious woolen fabrics while 45 traveling in continuous sheet form, in combination, a housing, means dividing the housing interior into a plurality of sections extending transversely of the length of the machine, means dividing each section vertically and transversely into

5 a pressure chamber and a suction chamber, a plurality of air-propelling and heating means arranged across the width of the housing and interposed between and in line with the pressure and suction chambers of a section producing a recirculating blast of air traveling in one direction in the pressure chamber and in the opposite direction in the suction chamber back to its respective air-propelling means, means disposing the fabric in vertical air-directing sheets 10 in a plurality of spaced and parallel runs in the pressure and suction chambers so that the runs compel the air blast to travel lengthwise of the fabric in each chamber from beyond the ends 15 of the runs, and means interposed between the discharge sides of the air-propelling means and the fabric to equalize the distribution of the air across and throughout the runs of the fabric.

9. A drier having in combination a housing, 20 means for propelling continuous material therethrough, baffle means subdividing the housing interior into a plurality of sections through which the material passes in sequence, separate fresh-air inlets from outside the housing and separate moist-air exhaust passages leading out from the housing for a plurality of the sections, preheating means warming the fresh air admitted from outside the housing into a plurality of the sections before mingling with the air being impelled therethrough, fan means for entering fresh 25 air, driving such air through one or more sections and discharging it from the housing when vapor-laden independently of the air-flow through other sections, and means optionally determining the occurrence and the amount of air-transfer between adjacent sections.

10. A carbonizing drier having in combination a housing approximating in width the width of the widest fabric desired to be treated, means for propelling continuous textile fabric material therethrough in a multiplicity of spaced vertical runs comprising a series of upper spaced rollers and a series of lower spaced rollers, vertical transverse partitions dividing the housing interior into a plurality of sections wherein differing conditions of heat and moisture may be maintained, secondary vertical transverse partitions separating adjacent vertical runs and di-

viding the sections into communicating pressure and suction chambers traversed by the material and each containing a series of the upper and lower spaced rollers, air-heating and air-propelling means wholly contained within the 5 width and height of the housing, above the floor on which the drier stands, and beneath and within the width of the material, recirculating heated air in one direction through a pressure chamber and reversely back to the same propelling means through an associated suction chamber, this air passing between and lengthwise of a plurality of runs of the fabric in each chamber.

11. A carbonizing drier for woolen fabrics having in combination a housing, means for propelling continuous material therethrough in oppositely travelling successive runs, means establishing a closed air-circulation path in which the air travels both from and to the air-propelling 15 means in contact with and along and guided by the surface of the fabric in a direction mainly lengthwise of the latter, air heating means, and the said air-propelling means comprising a plurality of blowers disposed across and wholly 20 within the width of the housing, below the runs of fabric and above the floor on which the drier stands, producing abundant and equalized air-flow across the entire width of the fabric while 25 permitting access to the housing interior from 30 both sides.

12. A carbonizing drier having in combination a housing, means for propelling continuous fabric material through the housing in oppositely travelling successive vertical runs, an air-heater 35 and a fan blowing air through the heater and thence between and lengthwise of these runs, both the heater and the fan being located within the housing below the runs, means returning this air to the same fan through which it has already 40 passed, beyond the ends of other vertical runs and thence between and lengthwise of such latter runs of the material, and a lint-catching screen horizontally disposed below the latter runs and above the fan across the path of the air as it returns to the said fan after leaving the material. 45

FRANK B. MORRILL.
